(57) **CLAIM**

The ornamental design for a lavatory, as shown and
described.

DESCRIPTION

In a preferred embodiment, the nature of this product is as
a plumbing fixture in the form of a lavatory which is
primarily useful for washing the body parts of humans.
FIG. 1 is a right, top, front perspective view of a lavatory
embodying my new design;

FIG. 2 is a top plan view thereof;

FIG. 3 is a front elevational view thereof;

FIG. 4 is a right side elevational view thereof, the left side
elevational view thereof being a mirror image of the right
side shown;

FIG. 5 is a rear elevational view thereof;

FIG. 6 is a bottom plan view thereof; and,

FIG. 7 is a cross-sectional view thereof taken along line
7—7 of FIG. 2.

The broken line representations of an outer rim in the figures
are for the purpose of illustration only, and form no part of
the claimed design.
